UNITED STATES PATENT OFFICE.

JARED MARIS, OF COLUMBUS, OHIO.

DESIGN FOR THE ORNAMENTATION OF HUBS.

SPECIFICATION forming part of Design No. 16,468, dated January 12, 1886.

Application filed November 28, 1885. Serial No. 184,224. Term of patent 14 years.

To all whom it may concern:

Be it known that I, JARED MARIS, a citizen of the United States, residing at Columbus, in the county of Franklin and State of Ohio, have invented and produced a new and original Design for Flanges or Bands for Wheel-Hubs, of which the following is a specification.

My invention relates to a design for the ornamentation of the flange of a wheel-hub; and it consists in a continuous series of pointed and blunt projections on the periphery of the flange, the said pointed and blunt projections being arranged alternately, as shown.

In the accompanying drawings, Figure 1 is a view in end elevation of a flanged shell-band embodying my design, and Fig. 2 is a plan view of the same.

A represents a flange having a continuous

series of alternately-arranged pointed projections, *a*, and blunt projections *b* on the periphery thereof. These projections have straight sides and are of a length sufficient to give the periphery of the flange an angular appearance.

Having fully described my invention, what I claim as new, and desire to secure by Letters Patent, is—

In a design for the flange of a wheel-hub, the ornamentation of the same, consisting of the alternately-arranged pointed and blunt projections on the periphery of the flange, as shown and described.

JARED MARIS.
